UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed October 22, 1924. Serial No. 745,253.

My invention relates to mining apparatus.

An object of my invention is to provide an improved mining apparatus. Another object of my invention is to provide an improved mining machine especially adapted to cut kerfs in a vertically disposed plane. Still another object of my invention is to provide an improved mining apparatus including a machine of the flexibly fed type, herein of standard construction, adapted to cut kerfs in a vertical plane and especially adapted to cut downwardly disposed kerfs in the coal strata in accordance with the "strip or open pit" system of mining. In improved means are provided for supporting the machine. A still further object of my invention is to provide an improved mining apparatus including a flexibly fed mining machine of the pivoted bar type, herein the standard form, having improved supporting means therefor wherein the machine may be turned on its side and cut kerfs in a vertical plane in accordance with the "strip or open pit" system of mining. In accordance with the "strip or open pit" method of mining the surface of the coal strata is cut in a series of narrow strips, blocks, or other desired sections. A still further object of my invention is to provide an improved mechanism especially adapted to use in the above system of mining. These and other objects and advantages of my invention will, however, hereinafter more fully appear.

In the accompanying drawings I have shown for purposes of illustration one form which my invention may assume in practice.

In these drawings,—

Fig. 1 is a side elevational view of a mining apparatus constructed in accordance with one illustrative embodiment of my invention.

Fig. 2 is an end elevational view of Fig. 1, the view being shown partially in section to facilitate illustration.

In this illustrative construction I have shown a mining machine designated as an entirety by the numeral 1 provided with a longitudinally extending frame 2. The frame 2 is comprised of three sections, that is, a motor section 3, a feed section 4, and a cutting mechanism carrying section 5, the feed and cutting mechanism carrying sections 4 and 5 being disposed at opposite ends of and rigidly connected to the motor section

3, in the usual manner. The frame 2 of the mining machine is disposed on its edge or side 6, with its bottom plate 7 disposed in a vertical plane, on a skid or support generally designated 8 of improved form to be hereinafter more fully described, which is slideable on the surface of the coal strata. It will herein be noted that for the purposes of moving the machine relative to the mine surface there is provided a flexible feeding member 9, herein in the form of a feed chain, which is secured at its outer end to a stationary extraneous abutment and is guided at its inner end by a plurality of guide sheaves or rolls 10 rotatable on horizontal axes on the feed frame section 4 and this flexible member is suitably drawn in, moving the machine relative thereto, by a feed operating member 11, herein a chain engaging sprocket, disposed on a horizontal axis on the feed frame, said axis being parallel to the axes of the guide sheaves. The feed operating member 11 is rotatable at a predetermined cutting speed or a predetermined fast speed, said fast speed being utilized in hauling the machine about the mine, in a well known manner. The feed operating member 11 is driven by the motor through suitable power transmission mechanism, not shown, which may be of any approved form. It will herein be observed that the frame section 5 carries a cutter bar 12 pivoted on a transverse horizontal axis 13 parallel to the axis of the feed sprocket 11 and which cutter bar is adapted to be swung downwardly into the coal strata, herein by extending the feed chain 9 beneath the machine and through an opening in the support 8 and connecting the same to a pivoted two-part hook 14 indicated by dotted lines in Fig. 1, which hook is in turn adapted to be connected to a laterally projecting abutment 15 suitably secured to the cutter bar. The feed sprocket 11 is then rotated at a slow or cutting speed drawing in the free end of the feed chain 9, swinging the bar from the dotted line position indicated in Fig. 1 downwardly, cutting a narrow vertical kerf in the coal strata until the bar reaches a position substantially perpendicular to the major axis of the machine frame 2. The cutter bar is then locked in position by means of a pin 16 which is adapted to register with one of a plurality of horizontally disposed openings 17 formed in a circular flange 18

which is adapted to guide the cutter bar during its swinging movement. Herein it will be noted that the cutter bar 12 is provided with an endless cutter bit carrying cutter chain 19 which is adapted to be circulated about the outer edge of the cutter bar by the motor 3 through suitable transmission connections, not shown, in a well known manner. Instead of utilizing the feed chain to swing the cutter bar downwardly into the coal strata the bar may be swung by the raking action of the cutter bits and by the weight of the bar.

As heretofore stated the mining machine 15 is of standard construction turned on its side and mounted on the skid or support 8 of improved form. In my improved construction it will be observed that a shoe or bottom plate 20 that is adapted to engage 20 the mine surface is provided, preferably having upturned curved front and rear ends 21 and slightly upturned curved side portions 22 to permit a free sliding movement of the bottom plate on the surface of the coal strata 25 and relative to a transport truck, not shown. As shown, a plate 23 is disposed longitudinally beneath the side 6 of the mining machine and is secured to the latter by means of screws 24, while operatively connected to 30 the bottom plate 20 are parallel longitudinally disposed laterally spaced angle members 25 and 26. A plurality of transversely extending supporting members 27 have their flattened portions secured to the angle members 25 and 26 and to the plate 23 by suitable rivets 29 and 28, respectively. As illustrated, transversely extending bracing members 30 are secured at their ends, which have been flattened, to the plate 23 and the supporting members 27 likewise by the rivets 28 and are provided with downwardly extending intermediate flattened portions which engage the bottom plate 20 and are secured thereto by suitable rivets 31. As illustrated, the bottom plate 20 and the supporting members 27 are further suitably braced by a longitudinally extending plate 32 which engages the intermediate flattened portions of the bracing members 30 and the bottom surfaces 35 of the supports 27 at spaced points along its length and is suitably secured to the bracing members 30 and the bottom plate 20 also by the rivets 31 and to the supporting members 27 by rivets 32. A plurality of angularly disposed bracing members 33, herein three, are disposed between the vertically disposed bottom plate 7 of the machine and the skid bottom plate and which braces are rigidly connected thereto by means of screws 34 and the rivets 29, respectively. A longitudinally extending angle member 35 disposed in a plane parallel with the angle members 25 and 26 is further provided to rigidly secure the machine to the skid and is secured thereto by means of

screws 36 and certain of the rivets 28. It will be observed that the bottom plate 20 of the skid and the supporting members 27 and the bracing members 30 and 32 cooperate to form an opening 37 beneath the machine through which the feed chain 9 passes during the bar swinging operation.

As a result of my improved construction it will herein be evident that it is possible to provide a stable support of improved form 75 for a mining machine constructed to operate in accordance with the "strip or open pit" system of mining and which is of an exceedingly simple and rugged character and which may be manufactured at a minimum of expense. These and other advantages will be clearly apparent to those skilled in the art.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining apparatus, a mining machine having a pivoted cutter bar movable in a vertical plane, means for swinging said bar including a flexible element, and supporting means for said machine including vertically spaced plates, an intermediate support, and transversely and longitudinally extending bracing members secured to said plates forming an opening through which said flexible element is adapted to pass.

2. In a mining apparatus, a mining machine normally cutting on its own bottom and having a pivoted cutter bar, and means for operating said machine with its bottom in a vertical plane comprising supporting means including an upper plate to which the side of said machine is secured, a bottom plate, and truss means for maintaining said plates in fixed spaced relation to each other.

3. In a mining apparatus, a mining machine normally cutting on its own bottom having a pivoted cutter bar, and means for operating said machine with its bottom in a vertical plane comprising supporting means including an upper plate to which the side of said machine is secured, a bottom plate, and truss means for maintaining said plates in fixed spaced relation to each other including a longitudinally disposed truss.

4. In a mining apparatus, a mining machine normally cutting on its own bottom having a pivoted cutter bar, and means for operating said machine with its bottom in a vertical plane comprising supporting means including a bottom plate, an intermediate support attached thereto, transverse and longitudinally extending bracing means therefor, and a plurality of longitudinally

spaced angular bracing members disposed between the vertically disposed bottom of said machine and said bottom plate.

5. In a mining apparatus, a mining machine normally cutting on its own bottom having a pivoted cutter bar, and means for operating said machine with its bottom in a vertical plane comprising supporting means including an upper plate to which the side 10 of said machine is secured, a bottom plate, transversely extending intermediate supports interposed between said plates, a plurality of transverse bracing members between said intermediate supports and said 15 bottom plate, and longitudinally extending angular bracing means secured to said intermediate support and said transverse bracing member.

6. In a mining apparatus, a mining machine normally cutting on its own bottom having a pivoted cutter bar, and means for operating said machine with its bottom in a vertical plane comprising supporting means including an upper plate to which the side 20 of said machine is secured, a bottom plate, parallel members secured to said bottom plate, transversely extending intermediate supports secured to said upper plate and said parallel members, transverse bracing 25 means secured to said intermediate support and said bottom plate, and longitudinally extending bracing means secured to said intermediate support and said transverse bracing members.

30 7. In a mining apparatus, a mining machine normally cutting on its own bottom

having a pivoted cutter bar, and means for operating said machine with its bottom in a vertical plane comprising supporting means including an upper plate to which the side 40 of said machine is secured, a bottom plate, parallel members secured to said bottom plate, transversely extending intermediate supports secured to said upper plate and said parallel members, transverse bracing 45 means secured to said intermediate support and said bottom plate, and longitudinally extending bracing means secured to said intermediate support and said transverse bracing members, and a plurality of longitudinally spaced angular bracing members 50 disposed between the vertically disposed bottom plate of said machine and said intermediate support.

8. In a mining apparatus, a mining machine normally cutting on its own bottom having a pivoted cutter bar, means for swinging said bar including a flexible element, and means for operating said machine with its bottom in a vertical plane comprising supporting means including an upper plate to which the side 55 of said machine is secured, means for maintaining said plates in fixed spaced relation to each other including a longitudinally disposed truss and a transversely disposed truss, and an intermediate support, said supporting means having an opening through which said flexible element passes.

In testimony whereof I affix my signature.

MORRIS P. HOLMES.
